UNITED STATES PATENT OFFICE.

ANTONIO NAPOLETANO, OF MILLTOWN, NEW JERSEY.

PLECTRUM FOR MUSICAL INSTRUMENTS.

1,184,561.

Specification of Letters Patent.

Patented May 23, 1916.

Application filed April 3, 1915. Serial No. 18,874.

To all whom it may concern:

Be it known that I, ANTONIO NAPOLETANO, a citizen of Italy, residing at Milltown, in the county of Middlesex and State of New Jersey, have invented new and useful Improvements in Plectra for Musical Instruments, of which the following is a specification.

This invention relates to plectra for musical instruments and more particularly to mandolin picks.

The principal object of the invention is to provide a simple and efficient holder for picks which will give a fine grip and permit 15 the proper tremolo action.

It is a further object of the invention to provide a device of this character which is flexible, in which the pick is removably held so as to be conveniently replaced when 20 worn or broken and in which the same grip is obtained as with the ordinary form of shell pick.

Further objects of the invention will appear as the following description is read in 25 connection with the accompanying drawings, and in which:-

Figure 1 is a perspective view. Fig. 2 is an enlarged sectional view.

In the specific embodiment of the invention as illustrated herein, I employ a holder 1 of the outline shown or any other suitable outline, said holder being constructed of 30 rubber or other similar flexible and resilient material provided with a longitudinal channel 2 and a through aperture 3 which exposes the pick in the center of the body of the holder 1, as shown, and provides a recess for the entrance of the flesh of the fingers, thereby increasing the grip obtained. The 35 channel 2 extends from the forward end of the body and to a point in the rear of the aperture and on opposite sides thereof. The 40 channel 2 extends from the forward end of the body and to a point in the rear of the aperture and on opposite sides thereof. The pick which may be constructed of any suitable material such as horn, shell, celluloid

or the like is forced into the channel against 45 the resiliency of the rubber and is, therefore, held within the channel by frictional engagement of the walls thereof upon the faces and edges of the pick.

With a device of this character picks may 50 be made considerably smaller than usual and may be readily replaced when broken or worn. At the same time the holder produces a covering which has great frictional qualities and which provides for a firm grip 55 upon the pick which is impossible with the smooth shell, celluloid or horn picks now in present use.

What is claimed is:-

1. In combination with an ovoid zither 60 pick, a one piece resilient holder provided with a through opening and a channel, the walls of which inclose the edge of the larger end of said pick.

2. In combination with an ovoid zither 65 pick, a one piece resilient holder provided with a longitudinally extending channel, the walls of which resiliently grip the edge of the larger end of the pick, and further provided with a pair of openings each communicating with said recess and the exterior 70 of the holder.

3. In combination with an ovoid zither pick, a one piece resilient holder provided with a longitudinally extending channel, 75 the walls of which resiliently grip the edge of the larger end of the pick and further provided with a pair of openings, each communicating with said recess and the exterior of the holder, each of said openings lying 80 parallel to one side of said pick.

In testimony whereof I affix my signature in presence of two witnesses.

ANTONIO NAPOLETANO.
